UNITED STATES PATENT OFFICE.

STACY POTTS, OF WASHINGTON, DISTRICT OF COLUMBIA.

COMBINED SHIRT AND SUSPENSORY BANDAGE.

SPECIFICATION forming part of Letters Patent No. 642,920, dated February 6, 1900.

Application filed July 8, 1899. Serial No. 723,226. (No model.)

To all whom it may concern:

Be it known that I, STACY POTTS, a citizen of the United States of America, residing at Washington, in the District of Columbia, have 5 invented certain new and useful Improvements in a Combined Shirt and Supporter, of which the following is a specification.

My invention relates to an improvement in combined shirts and supporters. Hitherto 10 articles of this character have been made in which the supporter portion depended from the rear of the shirt and was adapted to pass forward between the legs and thence upward, where it was secured over the lower portion 15 of the abdomen by means of lacing, hooks and eyes, strings, or what not; but the objection to this form of device is apparent, first, because any material between the legs is liable to chafe and heat that portion of the body 20 and become soiled. There is the still further objection, and by no means the least objectionable feature, to wit, that the supporter when constructed and fastened in this manner has to be repeatedly loosened and unfastened when the wearer has occasion to exercise the natural bodily functions.

The object of my invention is to provide a combined shirt and supporter which will obviate the foregoing objectionable features 30 and at the same time afford an adjustable supporter for the scrotum alone without requiring unfastening except when the shirt is removed from the body; and with these objects in view the invention consists of a shirt having 35 a depending flap at its lower forward end, with means for adjusting and securing the flap beneath and around the wearer's testicles and with an orifice for the penis.

The invention still further consists in certain 40 novel features of construction and combinations of parts, which will be hereinafter more fully described, and particularly pointed out in the claims.

In the accompanying drawings, Figure 1 is 45 a front view of a shirt, showing the flap in its normally-lowered position, with draw-strings attached for fastening and adjusting the flap. Fig. 2 is a similar view showing the flap in its raised position. Fig. 3 is a view from the rear, 50 and Figs. 4 and 5 are details.

A represents a shirt of ordinary construction and B is a flap formed at the lower end

thereof, preferably as a continuation of the material constituting the shirt. This flap is, by preference, slightly curved or rounded at its 55 lower end, where it is folded over into a hem 1. At the side edges one or more, and usually at least two, eyelets 2 and 3 are formed in the flap, and above these eyelets and in the body of the shirt the additional eyelets 4 4 are 60 made.

A draw-string C is passed alternately inward and outward through these eyelets and through hem 1, its two ends extending outward, as indicated, in convenient position to 65 be pulled to adjust the flap and give it the desired tension. As a result of this construction and arrangement the draw-string can be pulled so as to give the flap the desired bag or pouch shape about the wearer's privates, 70 and by means of the draw-string passed loosely through the eyelets and hem the string can be drawn a greater or less amount, as required, from either end, so that the adjustment is rendered perfect. By the particular 75 method of passing the string in and out through the eyelets the sides of the flap are drawn together into a tightly-folded position, whereas the lower edge, where the hem is formed, is not drawn so tightly, but yet with 80 sufficient tension to fit the body at that point. When drawn to the required position, the strings are tied together, and the parts remain as adjusted. The orifice 6 is formed for the penis. Thus it will be seen that only the testicles are enveloped in the supporter, so that 85 the shirt with attached supporter can be worn with the utmost convenience and comfort. At the same time there is no difficulty in washing the garment. Neither is there any 90 difficulty in manufacturing the article, as the entire garment can be made in one piece.

In the manufacture it might be desirable to place a reinforce back of the portion of the shirt containing the eyelets and orifice. This, 95 of course, would be entirely within the discretion of the manufacturer of the goods and in accordance with the exigencies of the trade.

Having thus fully described my invention, what I claim as new, and desire to secure by 100 Letters Patent, is—

1. As an article of manufacture, a shirt having a flap formed at its lower forward end, said flap having a hem at its lower edge and

a draw-string having loose sliding connection through said hem and a portion of the shirt and adapted to be drawn and tied at its ends for the support and adjustment of the lower 5 and side edges of the flap.

2. As an article of manufacture, a shirt having a flap at its lower forward end depending from the body portion of the shirt and having an orifice therein for the purpose specified, 10 the lower edge of the flap rounded and folded

over to form a hem, eyelets formed at the edges of the flap and in the body of the shirt, and a draw-string passed in and out through said eyelets and through the hem for adjusting the flap.

STACY POTTS.

In presence of—

VERNON E. HODGES,
RALPH S. WARFIELD.
